DESCRIPTION

FIG. 1 is a front elevational view of a drive unit for a golf trolley showing our new design;

FIG. 2 is a top plan view of the drive unit for a golf trolley;
FIG. 3 is a right side elevational view of the drive unit for a golf trolley; and,

FIG. 4 is a bottom plan view of the drive unit for a golf trolley.

While FIG. 1 illustrates the front elevational view of the drive unit for a golf trolley, the rear elevational view of the drive unit for a golf trolley is the same.

While FIG. 3 illustrates the right side elevational view of the drive unit for a golf trolley, the left side elevational view of the drive unit for a golf trolley is the same.
